UNITED STATES PATENT OFFICE.

ANTONIO C. PESSANO, OF PHILADELPHIA, PENNSYLVANIA, ASSIGNOR TO THE GEORGE V. CRESSON COMPANY, OF SAME PLACE.

DESIGN FOR A PILLOW-BLOCK.

SPECIFICATION forming part of Design No. 32,590, dated April 24, 1900.

Application filed March 19, 1900. Serial No. 9,333. Term of patent 14 years.

To all whom it may concern:

Be it known that I, ANTONIO C. PESSANO, of the city and county of Philadelphia, in the State of Pennsylvania, have invented a new 5 and original Design for Pillow-Blocks, of which the following is a specification.

The accompanying drawings show a pillow-block embodying my design.

A is a flat base upon which is located a centrally-disposed and longitudinally-arranged box B, projecting at either end, as at b b, beyond the ends of the base A, so that the sides of 15 the base A form lateral horizontal flanges a a.

C is the cover or top of the box B, having its surface transversely arched and slightly curved longitudinally and provided with a central boss c and longitudinal side flanges e.

20 D D D D are four vertical column-like extensions from the sides of the box B and its cover or top C, which project outward upon the lateral sides a a of the base A.

The box B and its top or cover C are provided with a cylindrical longitudinal opening 25 or passage-way E, extending from end to end.

The side flanges a a of the base A are provided with perforations f f, located between the columns D D on each side.

The essential features of the design are the 30 base A, with the longitudinally-arranged and centrally-disposed hollow box B C projecting therefrom at each end, and the four vertical column-like lateral extensions D D from the box B C, projecting laterally upon the side 35 a a of the base A.

What I claim as new, and desire to secure by Letters Patent, is—

The design for a pillow-block substantially as described and shown in the accompanying 40 drawings.

In testimony of which invention I have hereunto set my hand.

ANTONIO C. PESSANO.
